J. SCHIFTER

OUTLET STRAINER

Filed Dec. 1, 1926

Patented Feb. 22, 1927.

1,618,679

UNITED STATES PATENT OFFICE.

JOHN SCHIFTER, OF NEW YORK, N. Y.

OUTLET STRAINER.

Application filed December 1, 1926. Serial No. 151,888.

My invention relates to improvements in strainers for waste outlets, and has for its object to provide a simple, cheap and efficient strainer and means for retaining it in connection with an outlet, whereby the retaining means may be detachably applied within an outlet fitting or pipe, the retaining means being adapted to fit securely within the bores of outlets of varying diameters within reasonable limits.

In carrying out my invention I provide a perforated strainer adapted to fit over a sewer outlet, such as the outlet of a sink, basin or other fluid container or a drain, and a retainer for the strainer comprising a block having bores at opposite ends respectively provided with right and left hand screw threads, and members fitting said bores and provided with corresponding right and left hand threads. When the threaded members are retained from rotation within the outlet and the block is rotated in an appropriate direction said members will be caused to travel outwardly from the block into engagement with the adjacent walls of the outlet, securing the block suspended in position therein, said block being provided with a transversely threaded aperture to receive a screw adapted to pass through the strainer, whereby the latter is secured in position over the outlet.

My invention comprises novel details of improvement that will be more fully herein-after set forth and then pointed out in the claims.

Reference is to be had to the accompanying drawings froming a part hereof, wherein—

Fig. 1 is a partly broken side elevation illustrating my improvement in use;

Fig. 2 is an enlarged detail vertical section substantially on line 2, 2 in Fig. 1;

Fig. 3 is a plan view of the strainer;

Fig. 4 is a detached perspective view illustrating parts for retaining the strainer;

Fig. 5 is a perspective view illustrating the position of parts when the retainer is being applied in an outlet, and

Fig. 6 is a perspective view illustrating a tool for holding the threaded members from rotation when the retainer is being applied to or removed from an outlet.

Similar numerals of reference indicate corresponding parts in the several views.

The numeral 1 indicates a perforated strainer which may be dome-like, as illus-

trated, or of any other suitable or well known form, adapted to fit over an outlet fitting or pipe 2 leading to a sewer, the outlet being of any well known form. I have shown the strainer 1 in an elongated form to extend upwardly from the bottom of the container 4 a substantial distance and the lower edge of the strainer provided with openings at 1^b, whereby if debris collects around the strainer water or other fluid will be able to flow or percolate through the apertures in the strainer for discharge. The outlet fitting 2 I have illustrated is of a well known tubular construction adapted to be connected to a sewer pipe 3 and applied to the bottom of any suitable container for fluid, such as a sink, basin, tank, drain or the like. The fitting 2 is illustrated at the bottom of a urinal 4. At 5 is a block, preferably of brass, of length less than the transverse diameter of the outlet 2 and provided at each end with a bore 6 which is internally threaded with right and left hand screw threads 7, 8 respectively at opposite ends adapted to receive members 9 and 10 which are respectively provided with right and left hand threads in mesh with the right and left hand threads of block 5. The members 9 and 10 are preferably provided at their outer ends with reduced or tapering portions at 9^a, 10^a to firmly impinge against the opposing walls of the outlet fitting or pipe. The block 5 is shown polygonal in shape so as to receive a tool, such as a wrench, for rotating the block. Said block is also provided with a transverse threaded bore 5^a to receive the threads of a screw 11, which screw is adapted to pass through a hole 1^a in strainer 1 with the head of the screw fitting against the walls of the hole, as illustrated in Fig. 2.

I provide means to retain the members 9 and 10 from rotation when the retainer is being fitted within the outlet. I have shown the members 9 and 10 provided with holes 12, near their outer ends, adapted to receive the prongs 13 on a resilient tool or holder 14, which may be made of wire bent as illustrated in Fig. 6 to provide two parallel arms 14^a extending from the bent portion 14^b, having two lateral portions 14^b carrying the prongs 13, the prongs 13 being bent at the free ends of the arms in a direction substantially transverse to the plane of the arms, so that when the prongs 13 are located in the holes 12 of the members 9 and 10

10 the retainer will be supported by said holder 14. The arms of the tool will move laterally when the attached members 9, 10 move relatively to block 5.

5 When the device is to be applied to an outlet the members 9 and 10 are screwed into the block 5 sufficiently far to permit said members to enter the outlet and said members are mounted upon the holder 14, 10 the prongs of the latter entering the holes of said members, whereupon the latter may be placed transversely within the outlet to the desired depth and can be retained by hand in desired position, and the tool or 15 wrench will be used to rotate the block 5 and the holder 14 will retain the members 9 and 10 from rotation. The rotation of block 5 with respect to the retained members 9 and 10 will cause the latter to travel 20 outwardly respecting the block and toward the opposing walls of the outlet into engagement with the latter, and sufficient pressure of the members against the walls of the outlet may be effected to cause the block to 25 be retained by the expansion or elongation of the retainer, so that the latter will be suspended within the outlet. The block 5 will be left in a position with its threaded bore or hole 5^a extending in the direction of the 30 axis of the outlet and this may be accomplished, if necessary, by individually rotating the members 9 and 10, slightly, by means of the holder 14 while the final position of the block is being effected. After the retainer has been secured within the outlet 35 the strainer 1 will be placed over the outlet and the screw 11 will be passed through the hole 1^a of the strainer and screwed into the hole 5^a of the retainer to secure the strainer 40 over the outlet, as illustrated in Fig. 2. By means of the right and left hand connection of members 9 and 10 with the retainer block 5 the hole 5^a in said block will always be brought to a substantially central or axial 45 position respecting the outlet when the retainer is being fitted within the latter, so that the hole 5^a of block 5 will be in a position to receive the screw 11 extending from the strainer irrespective of the extent of

projection of the members 9 and 10 outwardly from block 5.

The arrangement described permits the application of a retainer with its adjustable members within outlets of different transverse dimensions, within limits of the retainer, and permits the ready removal of the retainer from an outlet when desired by merely holding the members 9 and 10 from rotation and unscrewing the block respecting the latter.

My invention is simple and cheap to manufacture, can be readily applied to and removed from an outlet, and permits the strainer readily to be applied and removed while the retainer remains secured within the outlet and without disturbing the retainer in any manner.

Changes may be made in the details of construction set forth, within the scope of the appended claims, without departing from the spirit of my invention.

Having now described my invention what I claim is:

1. A device of the character described comprising a perforated strainer to fit over an outlet, a retainer to be fitted within the outlet comprising a block provided with members at opposite ends to engage opposite sides of the outlet, said block and members having cooperative threads for causing outward and inward movement of the members relatively to the block, the block being provided with a threaded transverse bore, and a screw to engage the strainer and the threaded bore in the block to retain the strainer over the outlet.
2. A device as set forth in claim 1, in which the cooperative threads between the block and members are respectively right and left hand at opposite ends of the block.
3. A device as set forth in claim 1, in which the members are each provided with a hole to receive a tool to retain the members from rotation when the block is being rotated to cause operation of the members relatively to the block.

JOHN SCHIFTER.
